UNITED STATES PATENT OFFICE.

CARL D. BROWN, OF HOPEDALE, MASSACHUSETTS, ASSIGNOR TO DRAPER CORPORATION,
OF HOPEDALE, MASSACHUSETTS, A CORPORATION OF MAINE.

CHUTE FOR FILLING-REPLENISHING LOOMS.

1,287,862.

Specification of Letters Patent. Patented Dec. 17, 1918.

Application filed May 11, 1918. Serial No. 233,852.

To all whom it may concern:

Be it known that I, CARL D. BROWN, a citizen of the United States, residing at Hopedale, county of Worcester, State of Massachusetts, have invented an Improvement in Chutes for Filling-Replenishing Looms, of which the following description, in connection with the accompanying drawing, is a specification, like characters on the drawing representing like parts.

This invention relates to weft replenishing looms preferably of the automatic type and its object is to provide means for catching and thus retaining the trailing end of the abandoned filling carrier after it is discharged from the shuttle in the operation of replenishment so that it will not be caught and carried by the shuttle or the fresh filling carrier into the cloth upon the succeeding pick.

This object is secured in the present invention by providing the chute which guides the discharging filling carrier with means for catching and retaining the trailing filling end preferably by serrating the upper edge of the chute.

The object also is to provide a chute capable of yielding both forwardly and rearwardly so that danger of breakage or of a smash is prevented if the filling carrier be caught between the chute and a moving part of the loom during its discharge and at the same time to provide means for insuring that the yielding chute shall always return to a definite normal position.

These and other objects of the invention will appear more fully from the accompanying description and drawings and will be particularly pointed out in the claims.

40. In the drawings,

Figure 1 is an end elevation partially in vertical cross section of so much of an automatic weft replenishing loom of the Northrop type as is necessary to a disclosure 45 of the present invention with a preferred form of the said invention embodied therein;

Fig. 2 is a front elevation of the transfer end of the lay shown in Fig. 1 together with a portion of the picker and picker guide, the chute and the parts concerned with the present invention in a preferred form;

Fig. 3 is a rear elevation of a portion of the chute supporting bracket and chute of the construction illustrated in Fig. 2;

Fig. 4 is an end elevation of the construction shown in Fig. 3 looking from the left;

Fig. 5 is a view similar to Fig. 3 showing a slightly different form of construction;

Fig. 6 is a view similar to Fig. 4 of the construction shown in Fig. 5.

The present invention is not concerned with the particular construction or operation of the general features of the loom to which it is applied. For convenience of 65 illustration the invention is shown in the preferred form selected as embodied in an automatic filling replenishing loom of the well known Northrop type.

In this type of loom the frame or loom 70 side 1 supports at the transfer end of the loom a hopper stand 2 upon which is mounted a rotary hopper 3 carrying the supply of fresh filling carriers 4. The lay 5 carries at the transfer end the shuttle box 6 75 and the lay and shuttle box are provided with a vertical opening 7 therethrough to permit the downward discharge of an abandoned filling carrier when the shuttle 8 is boxed at the transfer end of the loom. A 80 transerrer 9 is pivotally mounted on the hopper stand and provided with a dog 10 which upon the call for filling replenishment is lifted into the path of a bunter 11 carried by the lay thus causing the trans- 85 ferrer to force a fresh filling carrier, in this case a bobbin 4, from the hopper 3 into the shuttle 8 and thereby discharge the abandoned or exhausted filling carrier or bobbin in the shuttle down through the opening 7. 90

The end of the filling extending from the abandoned filling carrier through the eye of the shuttle is usually, in feeler looms, severed by suitable mechanism adjacent the nose of the shuttle and this severed end must 95 be drawn back through the eye of the shuttle and clear of the shuttle or it is liable to be caught by the shuttle or by the fresh filling carrier and dragged back into the shed and woven into the cloth causing an 100 imperfection.

In the construction therein illustrated the discharging filling carrier upon passing through the opening 7 is guided by an end guide and a plate or chute clear of the 105 working parts of the loom and falls into a suitable receiver or bobbin box placed on the floor beneath.

The end guide 12 may be of any suitable construction such as the plate shown with a forwardly projecting edge and supported by a bracket 13 depending beneath the lay and 5 acts to prevent the filling carrier from end-wise movement toward the body of the loom.

The chute comprises a flat guiding plate 14 journaled on a suitable support herein shown as a bracket 15 projecting from and carried 10 by the loom side 1. This bracket carries a laterally extending journal pin 16. The chute plate 14 is secured by rivets or screws 17 to a base plate 18 provided at its ends with downwardly projecting bearing lugs 19, 15 20. These lugs are apertured to provide bearings fitting over the journal pin 16 and these bearing apertures are slightly larger than the pin 16, the one 21 at the right being preferably elongated as shown in the drawing. 20 The chute supporting bracket 15 is provided with a positioning surface which in the construction shown in Figs. 3 and 4 is a flat surface 22 formed on the top of the upstanding portion of the bracket and the chute is provided with a corresponding chute position 25 defining surface which in the construction shown in Figs. 3 and 4 is a corresponding flat surface formed on the bottom of a lateral projection 23 from the lug 20. A 30 helical spring 24 connected to the lower portion of the lug 20 and to a projection 25 from the chute supporting bracket 15 acts to hold these chute positioning surfaces in contact and thus cause the chute to be maintained in 35 normal position. This spring preferably extends in line with the journal axis and normal to the contacting surfaces which surfaces extend preferably parallel with the journal axis.

40 The normal position of the chute is preferably about as illustrated in the drawings and is such that when the lay beats up the chute standing at a rearward inclination just contacts at its upper edge with the rear wall 45 of the opening 7 so that the discharged filling carrier forced out through the opening 7 slides down and is guided by the chute into the usual receiver or receptacle placed beneath the hopper. It is difficult to obtain 50 this precise relation of the chute and rear wall of the opening in practice owing to the wear which takes place in the loom parts, the difficulty of accurate adjustment and the liability for the lay to overthrow slightly, 55 and hence the chute is made to yield forwardly and thus rock on its journal with the lay so as to maintain at all times its upper edge in contact with the wall 7. This construction also prevents any danger of a 60 smash occurring if by chance a filling carrier in its discharge in some way gets behind the edge of the chute.

In order that the trailing end of the filling 65 may be caught and retained the upper edge 35 of the chute is provided with serrations 26

pointing toward the right. As the lay starts on its return movement after transfer the trailing end of the filling is caught over this serrated edge and is caught and retained thereby so that it cannot be carried back by 70 the shuttle or the fresh filling carrier into the shed.

If the filling carrier in descending on the chute should be caught by a moving part of the loom such for example as the bunter 75 11 while the lay was moving rearwardly it might get wedged in against the chute 14 and break or injure the chute and this not infrequently happens. To prevent this the means described permits the chute to yield 80 rearwardly.

Whenever the means which causes the chute to yield or pivot in either direction ceases to act the spring 24 immediately restores the chute to normal position defined 85 by the contacting positioning surfaces and thus the chute is always in position to perform its functions. It will be seen that as the chute is rocked or swung in either direction the positioning surfaces separate and 90 the chute is cammed out of normal position by the corners of the upstanding portion of the bracket 15. This camming action requires that the chute shall be loosely journaled and also that the bearing at the right 95 hand end shall be slightly elongated as illustrated.

It is obvious that the positioning surfaces may be variously disposed and variously shaped the only requirement being that they 100 shall be so shaped and positioned as immediately to restore the chute to its normal position under the action of the spring when the deflecting force has been removed.

In Figs. 5 and 6 another form of construction embodying the invention is illustrated. In this construction the upstanding portion 27 of the chute supporting bracket is extended horizontally at its top and the journal pin 28 projects laterally from the rearward portion thereof. The bearing lugs 29 and 30 extend forwardly from the bottom of the chute and the positioning surfaces are formed by the vertical contacting surfaces of the lug 30 and upstanding portion 110 27 of the chute supporting bracket. Consequently, also, the helical spring 31 is arranged horizontally. It will be seen that the functioning of the parts is, however, very similar to that shown in Figs. 3 and 4. 115 120

Having fully described my invention, what I claim as new and desire to secure by Letters Patent is:

1. In a weft replenishing loom, a lay provided with a shuttle box and having an opening therethrough to permit the discharge of the abandoned filling carrier, a chute support mounted on the loom frame, a chute journaled in said support extending upwardly therefrom and acting to receive and 125 130

guide the discharged filling carrier, means acting to permit the chute to swing yieldingly both forwardly to insure contact with the lay on the beat up and to prevent a smash if the discharging filling carrier passes behind the chute and rearwardly to prevent a smash if the discharging filling carrier is caught between the chute and a moving part of the loom, contacting surfaces on the chute and chute support acting to maintain the chute in normal position, and means acting to restore the chute to normal position with said surfaces in contact when the chute is swung in either direction.

2. In a weft replenishing loom, a lay provided with a shuttle box and having an opening therethrough to permit the discharge of the abandoned filling carrier, a chute support mounted on the loom frame and provided with a chute position defining surface, a chute journaled in the chute support and provided with a positioning surface normally in contact with said position defining surface, and a spring connected to the chute and acting to maintain said surfaces in contact whereby when the chute is

swung forwardly as by the lay or as by a discharging filling carrier or rearwardly as by a discharging filling carrier becoming caught between it and a moving part of the loom the spring is distorted and immediately acts to restore the chute to normal position.

3. In a weft replenishing loom, a lay provided with a shuttle box and having an opening therethrough to permit the discharge of the abandoned filling carrier, a chute support mounted on the loom frame, a chute loosely journaled in said support, flat coöperating positioning surfaces on said chute and said support extending parallel with the journal axis, and a spring connecting said chute and said support and extending in line with said axis and normal to said surfaces whereby when the chute is swung forwardly as by the lay or as by a discharging filling carrier or rearwardly as by a discharging filling carrier becoming caught between it and a moving part of the loom the spring is distorted and immediately acts to restore the chute to normal position.

In testimony whereof, I have signed my name to this specification.

CARL D. BROWN.
